Howson & Howson.

UNITED STATES PATENT OFFICE.

WALTER D. BUTZ, OF NORRISTOWN, PENNSYLVANIA.

STOCKING.

Application filed September 6, 1922. Serial No. 586,435.

The object of this invention is to provide a novel stocking of highly ornamental appearance and of great strength and durability.

5 In the attached drawings:

Figure 1 is a side view of the lower portion of a stocking embodying my invention, and

10 Fig. 2 is a fragmentary development of a portion of the stocking showing the panel construction.

15 In forming my stocking, I may and preferably do knit the upper portion, 1, of the leg to a point at or slightly above the ankle in the usual manner. At this point, I introduce with the knitting thread an auxiliary or "splicing" thread or a number of such threads, or I otherwise render the fabric heavier as by using a thread or threads of 20 greater weight than was employed in knitting the upper portion, 1, of the stocking.

25 Where the "splicing" thread is employed, this method being preferred by reason of greater simplicity, I knit from the point of introduction one or more consecutive courses completely around or across the stocking, whereby in the completed article there is formed a band, 2, of the heavier fabric completely around the stocking. I then for one 30 or more courses float the "splicing" yarn across that portion of the fabric which constitutes in the finished article the front of the stocking, the length of the floats being such as to give a predetermined desired effect. Following the course or courses in 35 which the "splicing" yarn is floated as described, I again knit one or more courses with the "splicing" yarn completely around or across the stocking with the formation of another complete band of the heavier fabric.

40 As a result of these consecutive operations, there is formed at the front of the stocking a panel, 3, of lighter fabric of predetermined width and breadth entirely surrounded by 45 the heavier material caused by introduction of the "splicing" yarn. Also, by alternating the aforescribed operations, I am able to provide a stocking having a series of such panels extending down the front, from any 50 point on the leg, depending upon the point

at which the "splicing" yarn is introduced, and, if desired, entirely across the foot, as illustrated in the drawings.

It will be apparent that a stocking made in accordance with my invention may have 55 all the advantages of what is commonly designated the double sole and high-spliced heel stocking, and that further the operations may be adjusted to give considerable variation in the appearance of the stocking. Variety 60 may also be had in the color or colors of the "splicing" yarn, or in employing as the "splicing" yarn one capable of taking a dye to which the normal knitting yarn is 65 immune.

It will be understood that the invention is not limited to the herein-described particular method of forming the panels, nor to any particular type or make of stocking, and that further there may be considerable variation 70 in design with no departure from the essential features of the invention.

I claim:

1. A stocking comprising a reinforced area at the back, with bands of the reinforced fabric extending at intervals across the front of the stocking and confining therebetween panels of the unreinforced fabric. 75

2. A stocking comprising an area at the back reinforced by splicing, with bands of the reinforced fabric extending at intervals across the front of the stocking and confining therebetween panels of the unreinforced fabric. 80

3. A stocking comprising a reinforced area at the back extending over approximately one-half the circumference of the stocking, and bands of the reinforced fabric extending at intervals across the front of the stocking and establishing at the front segregated panels of unreinforced fabric. 85

4. Stocking comprising reinforced areas at the back and under the foot, with bands of the reinforced fabric extending at intervals across the front of the stocking and over the foot to form a series of panels of the unreinforced fabric extending down the front of the stocking and over the foot. 95

WALTER D. BUTZ.
